UNITED STATES PATENT OFFICE.

JOHN H. GUNNISON, OF MADISON, WISCONSIN, ASSIGNEE TO RUSSELL GRADE MANUFACTURING COMPANY, OF MINNEAPOLIS, MINNESOTA, A CORPORATION OF MINNESOTA.

APPARATUS FOR MAKING AND HANDLING AGGREGATES.

Application filed November 2, 1922. Serial No. 598,689.

My invention relates to the preparation of aggregates such as are commonly employed in road making, and concrete construction work.

One object of the invention is to simplify and cheapen the process of preparing aggregates.

Another object is to complete the preparation with as little apparatus as possible. One important item in the accomplishment of this object is to handle the material in such a way that one passage from one supply or pile to another completes the preparation. Where the material in situ forms the supply this reduces the number of containers required to none in case receivers are available to receive it as delivered, and to one even if it must be stored for periodical delivery.

Another object is to provide a unitary portable outfit capable of receiving smooth material of all sizes, and delivering a good aggregate sized to a definite maximum size of particle.

Another object is to provide a unitary combined rock crusher and sorter.

Another object is to provide a single screen for sorting material both before and after it has been through the crusher.

Another object is to provide a very simple driving connection between the screen and crusher, and simple means for controlling the action of the screen.

Another object is to reduce the total equipment and improve portability. One item involved in the accomplishment of this object is to provide for transportation of the crusher by the same source of power used to drive it.

Further objects and advantages of the invention will become apparent as the description proceeds.

In the accompanying drawings:

Figure 1 is a more or less diagrammatic side elevation of the novel portion of an apparatus according to my invention;

Fig. 2 is a section substantially on line 2-2 of Fig. 1;

Fig. 3 is a central section of the crusher

I prefer to employ;

Fig. 4 is an enlarged detail of the screen mounting; and

Figs. 5 and 6 are a side elevation partly in section and a plan view, respectively, of an

adjustable mounting for the container or bin;

Fig. 7 is a side view, partly in section of a modification for heavy duty work.

In the embodiment of apparatus according to my invention selected for illustration, the chassis 10 carries a rock crusher 12 at its rear end, a motor 14 near its front end, a receiving hopper 16, and an oscillatory screen 18 positioned to take material from hopper 16 and deliver it to the crusher.

The construction of the crusher per se forms no part of my present invention. It may be briefly described with reference to Figure 3 as comprising a frame 20 provided with a removable stationary jaw 22 and a removable moving jaw 24 carried on bracket 26. At its lower end bracket 26 is adjustably held at a predetermined spacing from jaw 22 by means of toggle plate 28 engaging a suitable socket in the rear of bracket 26, and a similar socket in the slideable backing block 30, adjustable toward and away from the fixed jaw by hand-wheel 32, which raises and lowers wedge 34. The combined fly-wheel and pulley 36 rotates on shaft 38, which shaft carries an eccentric portion 40 rotating in a suitable bushing 42 in the upper end of bracket 26. A suitable tension rod 44 under the force of spring 47 prevents the parts from letting toggle plate 28 slip out of place when the device is not under mechanical stress to hold the parts together.

Material may be delivered to hopper 16 in any suitable way. Where the outfit is set up at the gravel pit, it is customary to provide an inclined track 44' up which a skip or dumping bucket may be drawn to convey material to hopper 16. A plurality of bars 46 form a grating over the top of the hopper to limit the maximum size received to any desired dimensions, but necessarily always at least to the maximum size which can be handled by the rock crusher. A suitable framework comprising uprights 48 and such cross pieces and braces as may be necessary, is provided for supporting hopper 16.

From hopper 16, the material passes, subject to control by a manually-operated gate 105 or cut-off 50 onto screen 18. The screen is preferably provided with suitable side pieces 52 to guide the material upon it in its travel

to the crusher. These side pieces and screen together form a chute with a foraminated bottom. Apertures 54 in the screen permit material below a certain predetermined size to fall through the screen so that it will not be delivered to the crusher. This material falls into an apron 56 terminating at 58 past the discharge point 61 of the crusher.

For oscillating screen 18, I mount a fitting 10 on bracket 26 for supporting a shaft 60 on which the end clips 62 of pitmen 64 are journaled. Similar clips engage pintles 66 carried by the screen intermediate its ends. It will be apparent that a rather rapid oscillatory motion will be imparted to screen 18 when the crusher is operating at its normal speed.

Referring now to Figures 2 and 4, rails 68 underlie the edges of screen 18, and 20 each rail carries short tracks 70 pivoted thereto as at 72 near each end thereof. Suitable brackets 74, one fastened to crusher 12 and another to one of the uprights 48, carry wheels 76 engaging tracks 70 to support 25 the screen and apron. I have provided suitable adjustment means for tracks 70 in the nature of sliding wedges 78 interposed between tracks 70 and rails 68, and adjustable by means of adjusting screws 80 and nuts 30 82 engaging the faces of brackets 84. It will be apparent that by the adjustment of track 70, the direction of the oscillatory movement of the screen may be adjusted within the limits of adjustment of the structure, to take care of different sizes and conditions of material. While I prefer to adjust the tracks so that the movement is one of translation without rotation, by setting all the tracks in parallel planes, it will be 35 apparent that by setting the tracks at opposite ends at different angles, a slight movement of rotation could also be employed if desired.

The apparatus hereinbefore described is 40 sufficient for certain classes of work, and operates as follows:—The operator stands on screen 18, and throws to one side pieces of material too large to pass between bars 46. By means of gate 50 he controls the 45 flow from the hopper to the screen, to deliver material to the crusher as fast as the crusher can handle it. The material falling through the screen travels down apron 56, and is joined before leaving the apron by 50 material falling from the discharge 61 of the crusher. In this way the lower end of apron 58 delivers the finished aggregate ready for use.

Under certain conditions, depending 55 on the nature of the material handled, and the exactness with which the maximum size of particle in the finished aggregate must be limited, it is desirable to return the discharge from the crusher to screen 18. This makes it possible to adjust

the crusher to deliver particles of maximum size considerably in excess of the diameter of holes 54, so that a fraction of the discharge from the crusher will always be returned to the crusher for a second pass before it is reduced to a size that will pass screen 18. This accomplishes two results. First, screen 18 is the element determining the size of particle delivered, rather than the crusher, and the maximum size can be 70 determined in this way with considerably greater accuracy. Second, the crusher can be set with a slightly wider discharge aperture, and will handle more material with such an adjustment.

The structure I have illustrated for returning the crusher discharge to the screen comprises a laterally directed chute 86 receiving the discharge from the crusher and delivering it to a suitable conveyor 88, which conveyor elevates the material and drops it on chute 90, from which it falls back on screen 18.

Conveyor 88 may be rendered operative or inoperative, simply by removing or replacing chute 86. Whether it is employed or not, the discharge from apron 58 will be the finished aggregate ready for use.

I prefer to employ a readily portable storage receptacle 92, see Figure 1, for receiving this aggregate, whenever it is necessary to store a certain amount of the aggregate for periodical delivery to wheel barrows, wagons, motor trucks, etc. This bin may be of the type described in my co-pending application, Serial Number 573,710, filed July 8th, 1922.

Any suitable conveying elevator may be employed to deliver the material from apron 58 to bin 92. I have illustrated a conveyor 94 driven by belt 96 from the crusher, so that motor 14, thru belt 98, may drive this conveyor as well as the crusher. Conveyor 88 may, if desired, also be driven from the other end of the crusher shaft, and is illustrated as provided with a drive pulley 100 for that purpose. Conveyor 94 may obviously be mounted on suitable scaffolding or standards. It may, if desired, have its lower end supported on brackets 102 removably bolted to the rear end of chassis 10.

I have provided means for transportation of chassis 10 and the equipment mounted thereon from place to place by means of power derived from the same engine 14 employed to drive the crusher. For this purpose the chassis is mounted on running gear comprising front wheels 104 controlled by steering wheel 106, and rear wheels 106' on axle 108 spaced from the chassis frame by 125 the usual springs 110 and carrying sprockets 112 for driving the same by means of suitable chains 114. A suitable change speed transmission 116 drives the jack-shafts 118'. 130

When one job is finished, motor 14 is unbolted and turned with its crank-shaft parallel with the longitudinal axis of the frame. It is then connected to transmission 116 and the outfit moves away under its own power to the next job, under control of steering wheel 106 and control levers 118.

To facilitate transportation of bin 92, it is adjustably supported on corner posts 120.

Referring to Figures 5 and 6 blocks 122 form the terminals of trusses 124 on the bin. Standards 120 terminate in angle uprights 126 carrying blocks 128 supporting jack-screws 130. Jack-screws 130 enter sockets 132 in blocks 122 to adjustably support the bin, the standards and trusses being held in alignment by sliding engagement of clips 134 bolted to a small block 136 fastened in the upright of truss 124 and overlying the edges of upright 126.

When the bin is in use, a truck with a dumping body can be driven under the bin and filled by means of the rotary measuring and discharge devices 138. When the outfit moves on, the same truck may be driven under the bin, and the bin lowered into place on the truck for transportation to another place.

Referring now to Fig. 7, I have illustrated an outfit designed for maximum capacity and portability. A suitable transmission for driving rear wheels 106 without disturbing the mounting of engine 14 has been provided, comprising in this instance chain 138, driving vertical shafts 140 through bevels 142. To increase the capacity of the unit, a hopper 144 is provided adjacent the opening of the crusher jaws, so that a pile of material can be constantly kept above this opening to feed the crusher as fast as it can handle the material.

Control gate 50 is still employed, but a slow moving power driven conveyor belt 146 is placed below the discharge opening of the hopper. This may be adjusted to automatically deliver material to screen and crusher at the highest constant rate they can handle, thereby eliminating one operator, who would otherwise have to attend constantly to the delivery of material to the screen and crusher.

Without further elaboration, the foregoing will so fully explain the gist of my invention, that others may, by applying current knowledge, readily adapt the same for use under various conditions of service. It will, for instance, be obvious that the size composition delivered may be controlled by varying the discard size, the size passed by the screen, and the setting of the crusher, or any or all of these factors. With certain size compositions of raw material a satisfactory aggregate can be made by crushing a large portion of the original material to a relatively large final size, while with some-

what different raw material a better aggregate could be obtained by crushing only a few of the largest pieces to a size much smaller than that passed by the screen. The first mentioned setting would give sharp 70 pieces in the larger sizes and smooth ones in the smaller sizes, while with the second the reverse would be true. Many modifications and alterations may obviously be made without eliminating certain features which may 75 properly be said to constitute the essential items of novelty involved, which items are intended to be defined and secured to me by the following claims.

I claim:—

1. In combination, a rock crusher having a moving jaw, an oscillatory chute delivering a material into said crusher, means connecting said chute and jaw to oscillate said chute, the bottom of said chute being foraminated to pass material below a certain size and deliver large particles to the crusher, an apron below said chute to catch the fines, said apron extending under the discharge opening of the crusher, and means for either returning the material that passes through the crusher to the chute or permitting such material to mingle with the material on the apron passing under the crusher. 80

2. In combination, a rock crusher, a receiving grating for limiting the maximum size to be handled, a screen receiving material that has passed said grating and delivering the coarse material to the crusher, conveying means receiving the fines from said screen, 85 and means for delivering material from said crusher either to said conveying means or to suitable elevating means by which said material is returned to said screen. 90

3. In combination, a rock crusher, conveying means to deliver material thereto, said conveying means being foraminated, whereby only material above a certain size reaches the crusher, and receiving means positioned to receive the material from said crusher and the material failing to reach said crusher, and deliver all the material as a mixed aggregate, or to return the material from the crusher to said foraminated conveying means for redelivery of the coarser part thereof to the crusher. 100

4. In combination, a hopper, power driven means for delivering material from said hopper at a constant rate, an oscillatory screen receiving said material, a crusher, and a second hopper positioned to receive material from said screen and hold it in a pile in and over the intake orifice of said crusher. 110

5. An apparatus of the class described, comprising, in combination, a frame, an apron mounted therein, screening means arranged thereover, a crusher arranged adjacent one end of the screening means adapted to receive and crush the material which is too large to pass through said screening means, 120 130

- and means for returning to said screening means the material passing through said crusher.
6. In an apparatus of the class described, 5 the combination of a frame, an apron therein, a grizzly adapted to receive the material and effect a preliminary separation, a crusher adapted to receive the coarse material from said grizzly, means for returning to 10 said grizzly, for final discharge into said apron, all material passing through said crusher, and means for delivering to a receiving means the material in said hopper.
7. An apparatus of the class described, 15 comprising a frame, an apron mounted therein, a screen arranged over said apron and whereto a body of coarse material is delivered, a crushing means arranged to receive the coarse tailings from said screen 20 which are too large to pass through the meshing thereof, and means arranged to receive such crushed material and elevate it for re-delivery to said screen for reseparation.
8. In apparatus of the class described, the 25 combination of screening means for separating material according to size, passing the smaller material therethrough and holding the larger material against passage therethrough, a crusher for receiving the larger 30 material directly from said screening means and means for returning to the screening means the material passing through the crusher.
9. In apparatus of the class described, 35 the combination of a receiver, screening means for delivering the finer material to said receiver and for separating the coarser material therefrom, an outlet from said screening means, a crusher directly below 40 said outlet to receive the coarser material directly from said screening means, and means for returning to the screening means the material passing through the crusher.
10. An apparatus of the class described, 45 comprising a frame, an apron mounted therein, an oscillating screen arranged over said apron and whereto a body of coarse material is delivered, a crushing means arranged to receive the coarse tailings from 50 said screen which are too large to pass through the meshes thereof, means arranged to receive the crushed material and elevate it for delivery to said oscillating screen for re-separation, said apron having a discharge 55 opening and means for receiving and conveying away the material discharged there-through.
11. An apparatus of the class described, 60 comprising a portable frame, an apron mounted therein, screening means arranged over said apron and whereto a body of coarse material may be delivered, crushing means arranged to receive from the said screening
- means the coarse tailings which are too large to pass through the meshes thereof, means 65 arranged to receive the material from the crushing means and elevate it for delivery to said screening means for re-separation, and conveying means to receive the material from said apron.
12. An apparatus of the class described, 70 comprising, in combination, a portable frame, an apron mounted therein, a screening means arranged above said apron, crushing means mounted at one end of said 75 screening means and adapted to receive the tailings from said screening means, and means for returning to the screening means the material discharged by said crushing means.
13. An apparatus of the class described, 80 comprising, in combination, an apron, a screening means located above said apron, a crusher arranged to receive the coarse material passing over said screening means, 85 a bucket conveyor arranged to return the crushed material to said screening means, a delivery conveyor arranged to receive the material discharged from said apron, and means for operating said crusher, said 90 screening means and said conveyors.
14. An apparatus of the class described, 95 comprising in combination with a portable frame having supporting and carrying wheels, an apron located in said frame, an oscillating screen extending lengthwise of said screen over said apron, a pair of crushing jaws extending transversely of said frame in position to receive material tailing over said screen, and means, also arranged upon said frame, to receive the material that passes between said crushing jaws, and operating to elevate and discharge it upon said screen.
15. An apparatus of the class described, 100 comprising in combination with a portable frame arranged upon supporting and carrying wheels, an apron located in said frame extending longitudinally thereof and supported thereby, a screen extending lengthwise 105 of said frame over said apron, means supporting said screen and permitting a longitudinal oscillation thereof, a pair of crushing jaws extending transverse of said frame and located thereon below the discharge end of 110 said screen, whereby material tailing over said screen passes into the space between said crushing jaws, means arranged in said frame to receive the material passing between said crushing jaws, and an elevator arranged to 115 carry up the material passing between said jaws and discharge it upon said screen.
- In witness whereof, I hereunto subscribe my name this 30th day of October, 1922.

JOHN H. GUNNISON.
